UNITED STATES PATENT OFFICE.

PACIFIC J. THOMAS, OF PITTSTON, PENNSYLVANIA.

REELING MACHINE.

Application filed July 22, 1926. Serial No. 124,176.

This invention relates to an automatic reeling machine and particularly to a skein winding machine adapted to wind a predetermined length of yarn in each skein and then stop, the counting wheel reversing during said stop so as to be ready when the operator starts the machine for the next skein.

An object of the invention is to furnish improved means for accomplishing this result on the ordinary skein winding machines provided with the usual stop motion mechanism and the like.

With the foregoing object outlined and with other objects in view, which will appear as the description proceeds, the invention consists in the novel features hereinafter described in detail, illustrated in the accompanying drawings and more particularly pointed out in the appended claims.

Referring to the drawings:

Fig. 1 is a rear elevation of a portion of a skein winding machine with the improved mechanism attached thereto.

Fig. 2 is a transverse sectional view taken vertically through the machine and showing the position of the parts while the skeins are being wound and before the mechanism has actuated to stop the skein reel.

Fig. 3 is a similar view looking from the opposite end of the machine.

Fig. 4 is a view similar to Fig. 2 but illustrating the parts in the position which they occupy after a predetermined length of thread has been wound on the reel and the reel has been halted.

Fig. 5 is a detail view of the reel shaft bearing.

In the drawings, 1 and 2 designate the side bars of the machine frame which support a reel shaft 3 carrying a reel 4 on which the skeins of thread 5 are wound. One end of the reel shaft is vertically movable in a bearing 6, having a supporting block slidably mounted in side bar 2, as shown in detail in Fig. 5, to permit a driven wheel 7 fixed on the reel shaft to be raised out of contact with a driving wheel 8 fixed on a driving shaft 9. Located at the opposite end of the machine from the wheels 7 and 8, is a stub shaft 9^a on which is mounted a rotatable worm gear 10 which is fixed to a drum 11. The gear 10 will be hereinafter referred to as the counting wheel, and arranged between this wheel and the drum 11 is an arm or pointer 12 which may be fixed to rotate

with the wheel 10, by any suitable means such as a set screw 13. As the arm 12 rotates with the wheel 10 during the operation of the machine, it is necessary to have a zero position for the arm at the beginning of the operation, and to take care of this, a stop 14 is fixed on the frame of the machine and is adapted to be engaged by the arm 12 when the wheel 10 rotates in one direction. The wheel 10 is actuated by a driving worm 15 fixed on a shaft 16 rotatable in a bracket 17 that is pivoted at 18 on the frame of the machine. The end of the shaft 16 remote from the worm 15, has a bevel gear 19 which is in constant mesh with a similar gear 20 fixed on the reel shaft 3.

From the foregoing, it will be seen that the driving shaft 9 rotates the wheel 8 and this wheel drives the wheel 7. In this way the reel shaft 3 is driven and the gears 20 and 19 actuate the worm 15 and the counting wheel 10. Consequently the arm 12, which rotates with the wheel 10, is moved away from the stop 14, and when a sufficient amount of thread has been wound on the reel, the arm 12 will strike a pin 21 mounted on a bell crank lever 22 that is pivoted at 23 on the frame of the machine. This bell crank lever has a weight 24 that normally holds

the end of one of its arms against a notched cam 25 fixed on a rock shaft 26 that extends throughout the length of the machine and is mounted in bearings in the frame members 1 and 2. Normally the bell crank lever arm extends into the notch of the cam and as shown in Fig. 3, it prevents the cam and rock shaft 26 from rotating in either direction. When, however, the arm 12 strikes the pin 21, it rocks the bell crank

lever 22 and the bell crank lever moves out of the notch of the cam, so that the cam may rotate in a clockwise direction, in Fig. 3. This movement of the cam is caused by a spring 27 which has one of its ends fixed at 28 to the frame of the machine and its opposite end connected to the depending arm of a lever 29, which is mounted on a pivot 30. A rod 31 is adjustably connected to the lever arm 29 and also to a lever 32 which is fixed on the shaft 26. When the bell crank lever 22 is drawn out of the notch of the cam 25 and the cam turns under the influence of the spring 27, the arm 22^a of the bell crank rides on the nose 25^a of the cam and is held in contact with the cam by the weight 24. Therefore, when the cam is moved in the

opposite direction, by means hereinafter described, the arm 22^a of the bell crank will again drop into the notch of the cam under the influence of the weight 24.

5 The purpose of the arm 24, bell crank 22 and cam 25, is to trip the lever 29 at the proper time to cause the worm 15 to be raised out of contact with the counting wheel 10, so that the counting wheel will stop counting 10 at the proper time. To accomplish this, the lever 29 is fixed to a lever 33 which engages by any convenient means as a slot and pin connection not indicated a link 34 provided at its upper end with a hook 35 which engages the shaft 16 when link 34 is raised by lever 33. The link 34 also carries a pivotally mounted weighted latch 36 to maintain the shaft 16 in engagement with the hook 35.

It will be seen from the foregoing description, that as soon as the arm 12 has rotated the required distance to permit a predetermined length of thread to be wound on the reel, the bell crank lever 22 will be tripped, the shaft 26 will be rocked and the shaft 16 25 will be raised to disengage the worm 15 from the wheel 10. Then the wheel 10 may rotate in the opposite direction under the influence of a weight 37 suspended on a cable 38 having one of its ends attached to the drum 11. 30 When the shaft 26 is rocked, it actuates an arm 39, Fig. 1, pivotally connected to the actuating link 40 of an indicator 41. This indicator visually notifies the operator that the skeins have been wound on the reel.

35 The rocking of the shaft 26 also causes the halting of the reel and this is accomplished by a lever 42 fixed on the shaft 26. This lever is normally in the position shown in Fig. 2 and it has a nose 43 which bears against a lever 44 that functions to raise the wheel 7 out of contact with the wheel 8. This lever 44 is pivoted at 45 to the frame of the machine. Referring now to Fig. 2, it may be seen that when the shaft 26 is permitted to 40 rock under the influence of the spring 27, the lever 42 will move in a counter-clockwise direction and force the lever 44 in the same direction, so that the shoe 46 of that lever will bear against the underside of the wheel 50 45 and lift the latter off of the driving wheel 8. This will stop the movement of the reel and of the shaft 16, and then the operator may remove the skeins from the reel. As the lever 42 moves to actuate the lever 44, it

55 is locked in position by a latch 47 carried by a bracket 48 fixed on the frame of the machine. This latch preferably consists of an angular piece of metal pressed toward the lever 42 by a spring 49, as seen in Fig. 1.

60 When it is desired to reset the machine, the operator releases the latch by rocking a lever 50 pivotally mounted at 51 and connected to the latch at 52. When the latch has been released, the lever 42 may be returned to 65 its normal position and this is accomplished

by turning the shaft 26 in the opposite direction. To permit this the shaft 26 is provided with a fixed eccentric wheel 53 connected to one end of a chain 54, the other end of the chain being connected to the depending arm 55 of a lever 56 of special shape. The arm 57 of this lever is connected by a link 58 to a treadle 59, pivoted at 60 and moved in one direction by a weight 61. The lever 56 also has a fork 62 provided with screws 63 which bear on opposite sides of the lever 44. From Fig. 2 it may be seen that when the operator presses on the treadle 59 the lever 56 will be turned in a clockwise direction. This will cause the arm 55 to actuate the eccentric 53 and turn the shaft 26 in a clockwise direction. At the same time the screws 63 carried by the yoke 62 will rock the lever 44 in a clockwise direction so that the shoe 46 will release the wheel 7 and permit the latter to again contact with the driving wheel 8.

Referring again to Fig. 3, it may be seen that as the shaft 26 rotates in the opposite direction, the spring 27 will be again placed under tension, the shaft 16 will be lowered and the arm 22^a of the bell crank lever will move into the notch of the cam after the nose 25^a of the cam has released the arm 22^a.

90 It is obvious that the shaft 26 may actuate a counting device to indicate the number of skeins wound by the machine.

95 From the foregoing it is believed that the construction, operation and advantages of the invention may be readily understood and it is apparent that changes may be made in the details disclosed, without departing from the spirit of the invention as expressed in the claims.

100 What is claimed and desired to be secured by Letters-Patent is:

1. In a reeling machine, a reel shaft provided with a reel, a driven shaft, a counting wheel actuated by the driven shaft, an arm movable with the counting wheel, a bell crank lever actuated by said arm, a cam controlled by said bell crank lever, a rock shaft controlled by the cam, and means actuated by the rock shaft for breaking the connection between the driven shaft and the counting wheel and for halting the movement of the reel shaft.

110 2. In a reeling machine, a reel shaft provided with a reel, a driven shaft, means for actuating said shafts, a counting wheel actuated by the driven shaft, an adjustable arm movable with the counting wheel, a bell crank lever actuated by the arm, a cam controlled by the bell crank lever, a second arm controlled by the cam, a second bell crank lever, a link connecting the second arm to the second bell crank lever, a second link connected to the second bell crank lever and means connecting the second link to the driven shaft,

- whereby when the cam is released by the first bell crank lever the second link may move the driven shaft out of engagement with the counting wheel.
- 5 3. In a reeling machine, a reel shaft carrying a reel, a driven shaft, means for actuating said shafts, a rock shaft, means for driving the rock shaft from the driven shaft and including control mechanism for preventing actuation of the rock shaft until the driven shaft has been turned a predetermined number of revolutions, a lever for halting the movement of the reel shaft, an arm arranged to move said lever in one direction, said arm being movable with the rock shaft, and an automatically operating latch for retaining said arm in position after it has moved said lever.
- 10 4. In a reeling machine as claimed in claim 3, an eccentric on said rock shaft, a flexible element connected to the eccentric and means for exerting force on the flexible member to move the arm in a direction away from said lever.
- 15 5. In a reeling machine as claimed in claim 3, manually controlled means for releasing said latch.
- 20 6. In a reeling machine as claimed in claim 3, an eccentric mounted on the rock shaft, a
- flexible element for exerting force on the 30 eccentric to move the arm away from said lever, and means engageable with the lever and connected to the flexible element to permit the operator to move the lever in one direction and to move the arm in the same 35 direction.
7. In a reeling machine as claimed in claim 3, indicating mechanism actuated by said rock shaft.
8. In a reeling machine, a reel shaft carrying a reel, a driven shaft, a driving shaft, contacting wheels on the reel shaft and driving shaft to permit the latter to actuate the former, a counting wheel actuated by the driven shaft, an arm movable with the 40 45 counting wheel, a weighted bell crank lever actuated in one direction by said arm, a cam controlled by said bell crank lever, a rock shaft controlled by the cam, spring actuated means also controlled by the cam for disconnecting the driven shaft from the counting wheel, and means actuated by the rock shaft for breaking the contact between the wheels on the reel shaft and the driving shaft.
- 50 55

In testimony whereof I affix my signature.
